UNITED STATES PATENT OFFICE.

FREDERICK S. DUESENBERG AND AUGUST S. DUESENBERG, OF ELIZABETH, NEW JERSEY.

INTERNAL-COMBUSTION ENGINE.

1,363,500.

Specification of Letters Patent. Patented Dec. 28, 1920.

Application filed April 14, 1913, Serial No. 760,851. Renewed June 24, 1918. Serial No. 241,689.

To all whom it may concern:

- Be it known that we, FREDERICK S. DUESENBERG and AUGUST S. DUESENBERG, both citizens of the United States, and both residents of the city of Elizabeth, county of Union, and State of New Jersey, have invented certain new and useful Improvements in Internal-Combustion Engines; and we do hereby declare that the following is 10 a full, clear, and exact description of our invention, reference being had to the accompanying drawings, and to the numbers of reference marked thereon, which form a part of this specification.
- 15 Although the evolution of the hydro-carbon or internal combustion engine has advanced far, the practical efficiency of such devices is much less than should be expected in view of the fuel consumption. This is undoubtedly due to several causes, among 20 which are incorrect valve construction and operation, and the sometimes large expenditure of energy required to operate the valves.
- 25 It is also true that in the T head type of engines of this class, the area of the cylinder exposed to the combustion of the charge is relatively large and inaccessible without the removal of the cylinder from the base, and 30 the accumulation of carbon therein soon detracts from the satisfactory operation of the engine. In many such engines also, the fuel charge, when admitted must travel a considerable distance before reaching the point 35 at which ignition occurs, and after ignition the spent gases of combustion are frequently retained in the cylinder longer than desirable on account of the arrangement of the exhaust valve relatively to the inlet valve.
- 40 Many engines of the class, too, are of a complicated nature, comprising many moving parts without adequate provision for thoroughly lubricating the same during the operation, with the result, of course, of decreased efficiency. Frequently, too, where 45 mechanically operated valves are employed, the operating mechanism therefor, as well as the valve stems, are exposed at all times to the atmosphere and dust and dirt, and 50 consequently imperfect lubrication or failure of lubrication, seriously affects efficiency.

Another defect in multiple cylinder engines, is sometimes found in the arrangement of the inlet and the exhaust manifolds,

the inlet manifold, for example, in a four cylinder engine, requiring four branches leading to the respective inlet valves, with the effect that imperfect charging of some of the cylinders results owing to the longer travel required for the incoming gas between the carburetor and the cylinder to be charged.

It is an object of this invention to afford a multiple cylinder internal combustion engine, in which the inlet valves are arranged in pairs in adjacent cylinders, and the exhaust valves likewise arranged in pairs in the next adjacent cylinders, the exhaust valves and the inlet valves being arranged in each cylinder in very close relation and with the ignition device in very close proximity to the inlet valve, so that the incoming and outgoing gases will travel the shortest possible distance in the cylinder and in a manner to exert the maximum energy of the combustion directly upon the piston head.

It is an object of the invention also to afford an engine of the class described comprising a plurality of cylinders, and having mechanically operated valves in which the inlet valve, the exhaust valve, and the sparking element are very closely related, and in which the operating means for the valves are at all times lubricated, both by direct force feed and by splash lubrication.

It is a further object of the invention to afford a relatively narrow combustion chamber directly above the piston and in communication therewith, and having arranged in one side thereof inlet and exhaust valves, and in the opposite side closely adjacent thereto, the sparking device, the side of the combustion chamber opposite said valves being so constructed as to permit of opening the same to permit the removal of the valves or to permit cleaning of the cylinders and combustion chamber.

The invention embraces many other objects, which will be more fully understood from the accompanying drawings, and from the specification, wherein a preferred form of our invention is exemplified.

In the drawings:

Figure 1 is a front end elevation of an engine embodying our invention, with the cover for the gear case removed.

Fig. 2 is a vertical section thereof.

Fig. 3 is a view in side elevation, broken away and partly in section.

Fig. 4 is an enlarged fragmentary detail section taken on line 4—4 of Fig. 2.

5 Fig. 5 is an enlarged, top plan view of the crank case, with the cylinders removed and the connecting rods in section.

10 Fig. 6 is a fragmentary sectional detail of the mechanism for effecting oil regulation in the crank case.

Fig. 7 is an enlarged, fragmentary section on line 7—7 of Fig. 4.

15 Fig. 8 is an enlarged, fragmentary detail vertical section of a part of the crank case and the pump.

Fig. 9 is an enlarged section on line 9—9 of Fig. 8.

Fig. 10 is a fragmentary section on line 10—10 of Fig. 6.

20 Fig. 11 is a similar section on line 11—11 of Fig. 6.

Fig. 12 is an enlarged, fragmentary detail of one of the rocker arms and the cam shaft.

25 Fig. 13 is an enlarged, fragmentary longitudinal section of the tubular rocker shaft.

As shown in the drawings:

The crank case 1, is constructed of cast metal in any suitable manner, and is provided, if desired, with transverse interior webs, on which, and at the ends of the crank case is journaled the crank shaft 2, which may be constructed, of course, as usual, the construction in this particular as to the bearings for the crank shaft, varying with 30 the size of the engine, and the number of cylinders employed. Said crank case is provided on its right side with a removable side plate 3 to afford access to the interior of the crank case, and at its top is provided with a 35 suitably apertured and seated base plate 4, which may be integral with the remainder of the crank case, if desired, and upon which seats and is rigidly secured the respective cylinders A, B, C, and D, which are rigidly 40 secured in place thereon in the usual or any suitable manner.

45 Said cylinders, as shown, are each provided at the top with a relatively narrow and upwardly extending combustion chamber 5, which communicates in the top of the cylinder and extends substantially parallel the crank shaft, and the top of the cylinder is so shaped as to afford a slight clearance above the piston when at the end of its exhaust, and its compression strokes.

50 Each of said cylinders is water jacketed, and the water jacket may be afforded by coring the cylinder when cast or in any suitable manner. Conveniently, on the right or ignition side of said engine, a removable plate 6, affords one wall of the water jacket, and by removal permits access to the interior of the water jacket for inspection or repair. For the remaining portion of the 55 periphery of the cylinder, and extending

well into the head thereof above and around the combustion chamber, the water jacket is preferably cored in the metal, as indicated by 7, and if desired, a top cover plate 8, may be provided to afford access to the interior of the water jacket by its removal.

60 Inlet and exhaust ports of relatively large size are provided at the left side of the combustion chamber and are closed by mechanically operated puppet valves 9 and 10 respectively, each of which is rigidly secured on a stem 11, which extends through a suitable bearing sleeve 12, seated in a suitable bore in the side of the engine cylinder adjacent the combustion chamber, as shown in 65 Figs. 4 and 7. Secured on the outer end of each valve stem 11, is a stop 13, between which and the wall of the cylinder engages a pushing spring 14, said spring acting at all times to hold its valve normally closed. As 70 shown, an oil aperture is provided in the bearing sleeve 12, for each valve stem, and opens upwardly at the outer side of the cylinder, as indicated by 15, in Fig. 7, whereby the oil (converted practically to a vapor by 75 the splash lubrication hereinafter described) finds access to the stem to cool and lubricate the same at all times.

75 The inlet valves are arranged in pairs in adjacent cylinders. In the construction 80 shown, in which four cylinders are used, the inlet valves 9, of the cylinders A and B, are closely adjacent each other, and between the exhaust valves for said cylinders, and in the cylinders C and D, the same arrangement is 85 maintained, so that the inlet manifold X, indicated in dotted lines in Fig. 3, requires but two branches for a four cylinder engine, one of the branches opening directly to the valves 9, in the cylinders A and B, and the 90 other of the same opening directly to the valves 9, in the cylinders C and D, while the exhaust manifold, as indicated also in dotted lines in Fig. 3, is provided with four 95 branches which lead from the respective exhaust valves and upwardly therefrom.

100 The right side of the combustion chamber, or that opposite the valves, is bored to afford relatively large threaded openings therein, one directly opposite each of the valves and threaded therewith are closures 115 16, for the exhaust valves, and 17, for the inlet valves, the latter of said closures being apertured to permit the insertion of spark plugs 18, in close proximity to the inlet 110 valve and directed toward the axis thereof, as shown in Fig. 4. Said closures, upon removal, permit ready removal of the respective valves through the opening therefor, and permit the hand to be inserted into the 120 cylinder to permit the cylinder to be thoroughly cleaned and any carbon therein removed, when desired, and without necessitating removing the cylinders from the 125 crank case.

Connected with the respective cranks of the crank shaft, are connecting rods 20, of course, one for each cylinder, and each engaged with a piston 21, which may be constructed in the usual or any suitable manner. The crank shaft is provided on its outer end with a gear wheel 22, which meshes with a larger gear wheel 23, secured on a cam shaft 24, and affording a two to one drive therefor, said cam shaft being journaled in the crank case extending longitudinally at the left side thereof, and provided with suitable cams for actuating the respective valves. Said gears are, of course, incased to permit the same to run in oil.

Journalized above the cam shaft, is a tubular shaft 25, journaled on which are rocker arms 26, one for each inlet valve, and one for each exhaust valve, the upper, longer end of each of which extends into engagement with the outer end of the corresponding valve stem, as shown in Figs. 2 and 3, while the lower end thereof, which may be provided with a suitable anti-friction shoe 27, extends into bearing against the cam shaft in position to be engaged and actuated by the appropriate and corresponding cam thereon, so that when the shorter end of said lever is actuated by the cam, the upper end is thrown inwardly with greater velocity, instantly affording full opening of the valve actuated thereby, which, upon release of said rocker arm by said cam, is instantly closed by the action of its valve spring 14.

The bearing on said tubular shaft 25, for the rocker arms, is supplied with force feed lubrication; so also is the lower end of said rocker arm, so that the friction occasioned by the engagement of said rocker arms by the respective cams, is reduced to a minimum. For this purpose, as shown, an oil compartment is provided in the bottom of the crank case, an inner floor or bottom 28, being provided therein, as shown in Figs. 2 and 8, the space beneath said inner floor affording an oil well or container, and communicating therewith at the bottom, and cored in the side of the cylinder, is a casing 29, providing a cylindric bore or chamber therein in open communication with said oil compartment at its inner side, as shown in Fig. 8. Said chamber is closed at its bottom by the threaded head 30, of a cylindric cage 31, which extends upwardly to suitable packing at the top of said casing to afford a tight joint, as shown in Fig. 8.

Rigidly secured in said casing, and projecting upwardly through suitable webs 32 and 33, in the side of the crank case, is a cylindric pump barrel 34, which extends to near the lower end of the cylindric cage,

and is there provided with an inlet passage 65 closed by the upwardly opening ball valve 35, or other suitable valve adapted to permit the inflow of the oil. Within said pump barrel is a reciprocating pump rod 36, which, at its lower end, fits closely in 70 said barrel to afford the plunger, and is provided with an axial passage therein controlled by an inwardly opening ball valve 37, and, as shown, said pump rod 36, extends upwardly with its head 38, in position to be engaged by a cam 39, on the cam shaft, said cam acting to force the pump rod downwardly. A spring 40, rests at one end on the web 33, and surrounds the pump barrel, and at its upper end engages the 80 head 38, of the pump rod and acts to throw the pump rod upwardly affording the intake movement of the pump.

As shown, the inner passage in the plunger communicates in a chamber 41, above 85 the plunger, and from which leads a pipe 42, which communicates in the bore of the tubular rocker arm shaft 25, so that the bore of said shaft is at all times filled with oil. At each bearing of the rocker arm on 90 said shaft, an oil port is provided which delivers the oil therethrough to the bearing for the rocker arm, as shown in Fig. 12, and connected in the hub of the rocker arm bearing, as shown in Figs. 2 and 12, is a 95 pipe or tube 43, which leads downwardly therefrom along the inner face of the rocker arm and delivers oil therefrom to the shoe 26, or to the end of the rocker arm engaged by the cam. Of course, the shoe 26, 100 may be adjustably secured upon said rocker arm, if desired, and if desired, adjusting means at the upper end of the rocker arm may be provided to vary the bearing of said arm on the valve stem. Conveniently also, 105 and particularly in the larger engines, an anti-friction roller may be provided on the lower end of the rocker to minimize friction from engagement of the cam with the rocker for actuating the same. These, in 110 engines of smaller size, are, however, not necessary.

Mechanism is provided for mechanically regulating the level of the oil in the crank case. For this purpose, as shown in Figs. 115 2, 6, 10 and 11, a shaft 44, tubular except at its ends, is journaled in the crank case conveniently near the front side thereof, and is held in place by suitable bearings 45, in the end of the crank case, and corresponding 120 bearings 46, intermediate the ends thereof, said shaft fitting closely in said bearings. Within the bearing 46, the shaft is slotted peripherally for approximately a third of the circumference, as indicated at 47, and directly beneath said shaft an oil port 48, is provided through the floor 28, of the crank case.

On the outer end of the shaft 44, is provided a crank arm 49, adapted to be manually actuated, and if preferred, may have connected therewith any suitable operating means whereby the same may be operated from the operator's seat, said operating means, for example, leading to the dash of an automobile. By means of said lever, the amount of oil retained in the crank case may be varied at will, inasmuch as the height of the oil in the crank case will always be determined by the longitudinal slots 50, in said shaft, through which the oil flows at its level and thence through the peripheral slots or ports 47, and the ports 47, into the bottom oil compartment. Of course, when the tubular shaft 44, is of considerable diameter, a depth of oil may be maintained in the crank case when the slot 50, in the shaft is turned upward, equal to the diameter of the shaft, and a less depth of oil may be maintained when the shaft is rotated to bring said slots 50, near the floor or bottom of the crank case.

When the engine is assembled, and properly adjusted, a closing plate 51, is secured in place, as shown in Figs. 1 and 2, to entirely inclose the rocker shaft, rocker arms, and all the operating or moving parts of the engine, the joints, of course, being preferably gasketed or being ground down to afford a tight fit and prevent escape of oil.

The operation is as follows:

The entire left side of the crank case being open, the oil within the crank case is driven into a fine mist, almost vaporous in character, which at all times bathes all the operating parts of the engine, affording efficient lubrication. The oil falling upon the valve stems 11, and passing into the oil ports 15, in the sleeves 12, insures cooling and thorough lubrication for the valve stems, and also lubrication for the point of engagement of the upper ends of the rocker arms with the ends of the valve stems, while the bearings of the rocker arms on the rocker shaft and the point of engagement thereof with the cams, are also thoroughly lubricated, so that minimum friction and resistance is afforded for the operation of the valves.

Inasmuch as the valves and stems and bearings therefor are cooled by the water jacket and oil spray (the inlet valves also being cooled by the expansion of the hydro-carbon mixture), it follows that under the direct thrust of the rocker arm there can be no tendency whatever to the warping, twisting or springing of the valve stems, thus one very potent source of inefficiency in internal combustion engines is obviated. Very slight power is required for operating the oil pump whereby the oil is kept in circulation from the oil well within the rocker

shaft, and thence back into the bottom of the crank case, for splash lubrication, whereby the crank shaft, piston and cylinder are at all times maintained satisfactorily lubricated.

The cycle of operation is as usual in four cylinder, four stroke internal combustion engines. However, as the inlet manifold has but two branches of equal length, owing to the inlet valves of each pair of cylinders being placed adjacent each other, it follows that an equal supply of the hydro-carbon mixture is afforded for each cylinder, thus affording uniform and efficient operation. Furthermore, the shape and position of the respective relatively high (but narrow) combustion chambers arranged above the axis of each cylinder, is such that the inlet valve of each cylinder at one side of the combustion chamber, is brought into very close relation with the ignition element, in this instance shown as an ordinary spark plug for jump spark ignition, so that when the mixture is admitted to the combustion chamber and compressed therein, the ignition terminals of the spark plug are practically at the center of the compressed mixture. This is important, inasmuch as it affords uniform and complete combustion of the entire charge instantaneously, the force thereof being expended directly upon the piston head and wholly in line with the axis thereof.

Not only does this arrangement of valves and spark plug add greatly to the efficiency of the engine, but a further and important advantage is found in the readiness in which the valves and the exterior of the cylinder may be inspected. Inasmuch as the closures 16 and 17 may be removed, when desired, thereby permitting the removal and replacement of the valves therethrough, and as well the combustion chamber may be cleaned when desired, through said apertures, thus enabling the engine to be maintained in a satisfactory operative condition and thoroughly cleaned within, without the necessity of disassembling the engine by removing the cylinders from the crank case.

In actual operation, an engine embodying the construction herein described, has been found by test to afford a large percentage of efficiency over engines of other constructions. We ascribe this largely to the relation and combustion of each cylinder, and the location of the ignition device approximately at the center of the compressed mixture, and the quick and easy acting valve mechanism.

Of course, it is to be understood that details of the construction will vary to a considerable degree with the size of the engine. For example, it is desirable to provide rollers on the cam ends of the rocker arms for large units and, in some instances, force feed lubri-

cation may be used elsewhere than as shown and described. We have, of course, shown but a preferred form of our invention, but we do not purpose limiting the patent otherwise than necessitated by the prior art.

We claim as our invention:

1. In a device of the class described, a crank case, a plurality of integrally connected cylinders mounted thereon and formed at their upper ends into narrow vertical combustion chambers, a crank shaft journaled in said crank case, pistons in said cylinders connected to drive said crank shaft, horizontally operating inlet and exhaust valves controlling the inlets and outlets of said respective combustion chambers, and spark plugs disposed in said chambers opposite said inlet valves.
2. In a vertical engine of the class described, a cylinder, a narrow offset compartment formed integrally at the upper end thereof, horizontally disposed inlet and exhaust valves communicating therein, a water jacket surrounding said cylinders and the inlet and outlet passages controlled by said valves, and removable closures disposed opposite each of said valves in said compartments permitting ready inspection of said compartments and valves without interference with said valves.
3. An engine of the class described, embracing upright cylinders, side by side, parallel and horizontally operating mechanically actuated inlet and exhaust valves for each cylinder, threaded closures opposite both valves to permit removal of a valve therethrough and the inspection of the cylinder and combustion chamber, and a spark

40
plug connected in one of said plugs for each cylinder.

4. An engine of the class described, comprising a cylinder, a narrow offset vertical compartment formed at the upper end thereof, a pair of valves mounted therein controlling the inlet and outlet to said compartment 45 for said cylinder, said valves mounted transversely the axis of the cylinder, removable plugs for said compartment one opposite each of said valves, and an ignition means projecting into said compartment 50 through one of said plugs substantially at the center thereof.

5. In an engine of the class described, a cylinder, a narrow vertical compartment formed above the upper end thereof and offset from the axis of the cylinder, inlet and outlet valves mounted transversely of the engine communicating with said compartment to control the flow to and from the cylinder through the compartment, said 60 compartment having ports in the walls thereof one opposite each of said valves, removable plugs closing said ports, and an ignition device mounted in one of said plugs 65 opposite the inlet valve to fire a charge for the cylinder compressed in said compartment.

In testimony whereof we have hereunto subscribed our names in the presence of two subscribing witnesses.

FREDERICK S. DUESENBERG.
AUGUST S. DUESENBERG.
